UNITED STATES PATENT OFFICE

FRANCIS F. JAMES, OF PHILADELPHIA, PENNSYLVANIA, ASSIGNOR, BY MESNE ASSIGNMENTS, TO TRAYER BOLT COMPANY, INC., OF ELMIRA, NEW YORK, A CORPORATION OF NEW YORK

AUTOMATICALLY ADJUSTABLE CONNECTION FOR SHACKLE BOLTS

Application filed July 20, 1928, Serial No. 294,154. Renewed April 5, 1932.

The invention relates to an automatically adjustable connection for connecting a spring with the shackle hangers or the like.

An object of the present invention is to improve the construction of shackle bolt connections and to provide an automatically adjustable shackle bolt connection which will be simple, inexpensive, practical and efficient and at the same time possess great strength 10 and durability and adapted to be readily applied to the springs and shackle hangers of automobiles and other vehicles.

A further object of the invention is to provide an automatically adjustable shackle bolt 15 connection of this character equipped with a cone bearing and adapted to take up the wear without liability of forming shoulders in the cone bearing.

Another object of the invention is to provide 20 an automatically adjustable shackle bolt connection in which the shackle bolt may be constructed in either a single cone bearing type or a double cone bearing type and which will prevent the shackle bolt in either type 25 from twisting or falling out and which will reduce the liability of breakage of the shackle bolt to a minimum.

Another object of the invention is to provide 30 an adjustable shackle bolt connection in which the parts will be thoroughly lubricated and practically dust-proof.

With these and other objects in view the invention consists in the construction and novel combination and arrangement of parts hereinafter fully described, illustrated in the accompanying drawings and pointed out in the claims hereto appended, it being understood 35 that various changes in the form, proportion and minor details of construction, within the scope of the claims, may be resorted to without departing from the spirit or sacrificing any of the advantages of the invention.

In the drawings:

Figure 1 is a side elevation of an adjustable shackle bolt connection of a single cone bearing type constructed in accordance with this invention.

Fig. 2 is a horizontal sectional view of the same on the line 2-2 of Fig. 1.

Fig. 3 is a detail sectional view of the shackle bolt.

Fig. 4 is a transverse sectional view of the shackle bolt connection taken on the line 4-4 of Fig. 1.

Fig. 5 is a side elevation of an adjustable shackle bolt connection of the double cone bearing type.

Fig. 6 is a horizontal sectional view of the same partly in reverse plan view.

Fig. 7 is a reverse plan view of an automatically adjustable shackle bolt connection of the double cone type showing a different arrangement of connecting bolts from that illustrated in Figs. 5 and 6.

Fig. 8 is a detail view of one of the sections of the shackle bolt or pivot.

Fig. 9 is a transverse sectional view on the line 9-9 of Fig. 6.

Fig. 10 is a transverse sectional view of an 70 adjustable shackle for connecting the eyes of two springs.

Fig. 11 is a longitudinal sectional view of the same.

Fig. 12 is a detail sectional view of one of 75 the double cone shackle pivots.

Fig. 13 is a detail sectional view of one of the shackle plates.

Fig. 14 is a horizontal sectional view of an 80 adjustable shackle bolt connection having a one piece shackle bolt with a double cone bearing.

Fig. 15 is a transverse sectional view of the same taken on the line 15-15 of Fig. 14.

Fig. 16 is a longitudinal sectional view on 85 the line 16-16 of Fig. 14.

Referring particularly to Figs. 1 to 4 inclusive of the accompanying drawings in which is illustrated an adjustable shackle bolt connection of a single cone bearing type, 90

1 designates a bearing bracket constructed of suitable metal and consisting of a horizontal plate or body portion riveted or otherwise secured at 2 to the frame or chassis 3 of an automobile or other vehicle and provided with inner and outer depending side flanges 4 and 5 having transversely aligned horizontally disposed bearings 6 and 7 through which passes a shackle bolt 8. The bearings 6 and 7 consist of cylindrical en- 100

largements or extensions projecting from the inner faces of the depending side flanges 4 and 5. The bearing 5 is provided with a cylindrical bore or opening 9 for the reception of a cylindrical end portion 10 of the shackle bolt and the other bearing 6 has a reduced opening 11 to receive a reduced cylindrical portion 12 of the said shackle bolt. The reduced cylindrical portion 12 of the shackle bolt is connected with the end portion 10 which is relatively large by a central tapered or cone portion which is arranged in a tapered opening 13 of a cone bushing 14. The cone bushing 14 which has a cylindrical exterior is arranged within the eye 15 of a spring 16 of the automobile or other vehicle to which the device is applied. The cone bushing is of a length corresponding to the width of the spring 16 and the ends of the cone bushing are arranged in flush relation with the ends of the eye 15. A thrust washer 17 is arranged on the reduced portion of the shackle bolt and is interposed between the cylindrical enlargement 6 of the flange 4 and the adjacent ends of the eye 15 and the bushing 14.

The reduced portion of the shackle bolt is provided at its outer end with a threaded portion 18 which is engaged by a nut 19 and a washer 20 is arranged on the threaded portion of the shackle bolt and is engaged by a coiled spring 21 located within an outer cylindrical recess 22 of the cylindrical enlargement 6 and is interposed between the inner end wall 35 of the recess and the said washer 20. The spring is placed under tension by the nut 19 and it operates to urge the cone bearing portion of the shackle bolt inwardly into the tapered opening of the cone bushing and maintain a tight engagement between such elements of the cone bearing and to take up any wear of the parts. The washer 20 which is of greater diameter than the recess 22 forms an end wall or closure for the same and is adapted to exclude dust therefrom and from the cone bearing. In order to prevent the shackle bolt from twisting it is provided with opposite horizontally disposed arms 23 located exteriorly of the bearing bracket and arranged in spaced relation with the inner depending flange 5 thereof and provided with smooth cylindrical openings 24 through which pass bolts 25 provided at their outer ends with heads 26 and having inner threaded terminal portions 27 which engage threaded openings 28 in the depending flange 5 of the bearing bracket and the said openings 28 are located at opposite sides of the cylindrical extension 7 of the flange 5. The reduced threaded terminal portions 27 of the bolts 25 form shoulders 29 which abut against the outer face of the flange 5. The bolts 25 form guides for the shackle bolt and permit the inward movement of the same under the action of the spring 21 and at the same time

the bolts prevent any twisting of the shackle bolt and thereby reduce the liability of breakage of the same and assist in preventing the shackle bolt from falling out.

The nut 19 may be locked against accidental retrograde movement by any suitable means.

The shackle bolt is provided with a central longitudinal lubricant passage 30 extending inwardly from the end having the arms 23 and enlarged at its outer end and interiorly threaded to provide a threaded socket 31 for the reception of a suitable closure plug 32 and also to enable a grease gun or other means for supplying lubricant to be connected to it. The inner end of the lubricant passage connects with a transverse passage 33 located at the inner end of the reduced cylindrical portion 12 of the shackle bolt and extending to the outer surface of the shackle bolt at the inner end of the cone portion 8 and communicating with a circumferential groove 34. The inner circumferential groove 34 is formed in the cone bushing and is located at the smaller end of the cone bearing portion 8. A circumferential groove 35 is formed in the shackle bolt and is located at the larger end of the cone portion 8. The circumferential grooves assist in the distribution of the lubricant and the thorough lubrication of the cone bearing and the grooves 35 and 34 also are adapted to enable the shackle bolt to be adjusted automatically by the coiled spring, by reason of preventing shoulders forming on the bolt. The cone bushing while preferably constructed of bronze may be made of any suitable material as will be readily understood. The shackle bolt and the other parts of the device may also be constructed of any preferred metal.

In Figs. 5 to 9 inclusive is illustrated automatically adjustable connections of a double cone bearing type in which the shackle bolt is composed of two sections 36 and 38 each consisting of an inner cone portion and an outer cylindrical portion 37 and provided at the outer end with oppositely disposed arms 39. The larger end of the cone portion of each shackle bolt section is of a diameter slightly less than that of the cylindrical portion 37 and a circumferential groove 40 is formed in the section between the cone portion and the cylindrical portion 37 to facilitate lubrication of the double cone bearing and also to prevent the formation of shoulders in the cone at that point by having removed the metal where the shoulders would form due to the adjustment of the sections in a cone bushing 41. The cone bushing 41 has a bearing opening 42 tapered inwardly from each end of the bushing and provided with a central cylindrical enlargement 43. The cylindrical enlargement 43 of the bearing opening of the cone bushing constitutes a lubricant chamber and is interposed between the

reduced or smaller ends of the cone bearing portions of the shackle bolt sections and provides ample space for the inward adjustment of the shackle bolt sections to take up the wear without liability of forming shoulders in the bushing at the smaller ends of the cone portions. The bushing 41 which has the cylindrical exterior is arranged in an eye 44 of a spring 45 and the cylindrical portions 37 of the shackle bolt sections are mounted in cylindrical extensions 46 of depending flanges 47 of a bearing bracket 48. The bearing bracket 48 is riveted or otherwise secured at 49 to the frame or chassis 50 of an automobile or other vehicle and the said cylindrical extensions 46 are provided with cylindrical openings 51 of uniform diameter throughout their entire length.

The cone sections of the shackle bolt are urged inwardly and maintained in tight engagement with the cone bushing by coiled springs 52 disposed on bolts 53 which in the form of the invention illustrated in Figs. 5, 6 and 9 extend entirely across the bearing bracket and pass through openings 60 in the side flanges 47 and through openings 61 in the arms 39 of the shackle bolt sections. The coiled springs are preferably housed in caps 62 which prevent spreading of the parts beyond the initial adjustment but shoulders may be formed on the bolts for the same purpose. The bolts 53 are provided at one end with a head 63 and are threaded at the other end at 64 for the reception of suitable nuts 65 which may be located on the bolts 53 by any suitable means. The coiled springs which bear against the head 63 and the adjacent arms 39 maintain a constant tension on the shackle bolt sections and automatically take up the wear of the double cone bearing.

Lubricant is supplied to the double cone bearing through a lubricant passage 66 extending entirely through the cone sections 36 and enlarged at its outer end at 67 and internally threaded to form a threaded socket 68 for the reception of a screw plug 69 similar to the screw plug 32 heretofore described. The socket is adapted to be connected with a grease gun or other suitable means for supplying a lubricant and any other desired form of closure may, of course, be employed for closing the outer ends of the lubricant passages and for confining the lubricant therein.

In Fig. 7 of the drawings coiled springs 70 are arranged on the inner portions of short bolts 71 and are interposed between the side flanges 47 and the heads of the bolts which have threaded outer ends and which are provided with nuts 72 designed to be locked against retrograde rotation by any suitable means. The springs and bolts which are arranged in pairs urge the shackle bolt sections inwardly and maintain a tight engagement between the same and the double cone bushing 41 to take up the wear. With the exception of

the short bolts arranged in pairs the double cone bearing connection illustrated in Fig. 7 is constructed exactly the same as the double cone type connection illustrated in Figs. 5, 6 and 9 inclusive. The short bolts pass through 70 the arms 39 of the shackle bolt sections and engage the outer faces of the arms as shown.

In Figs. 10 to 13 inclusive of the drawings is illustrated an adjustable shackle bolt connection for connecting the adjacent ends of 75 two members 73 and 74. The shackle bolt connection comprises upper and lower single piece shackle bolts 75 having central cylindrical portions which are arranged in eyes 76 and 77 of the springs 73 and 74. The shackle 80 bolts 75 are provided with cone terminal portions 78 which are arranged in cone bearing recesses 79 of shackle plates 80 located at opposite sides of the members and connected by a central bolt 81.

The shackle bolts 75 are tubular and they are provided with circumferential grooves 82 located between the ends of the central cylindrical portions of the shackle bolts and the adjacent ends of the cone portions 78 and 96 are adapted to prevent formation of shoulders on the bolt and in cone recesses 79 thereby insuring proper engagement with the cone bearings 78. The tubular shackle bolts permit the lubricant to pass through the shackle bolts from one cone bearing to the other and the shackle plates are provided at the reduced ends of the cone bearing recesses 79 with cylindrical enlargements 83 which provide the necessary space for the relative adjustment of the shackle bolts and shackle plates to take up the wear, without forming shoulders in the shackle plates 80. The enlarged recesses 83 also provide lubricant chambers or spaces to enable the lubricant to readily 105 flow to the cone surfaces for lubricating the same.

The shackle plates 80 are provided at their side edges with two spaced webs 84 to prevent bending of the shackle plates and the central connecting bolt 81 passes through the shackle plates between the webs, and is provided at one end with a head 85 and at the other end with a nut 86 arranged on the threaded terminal portion of the bolt 81. A coiled 110 spring 87 is disposed on the bolt 81 and is interposed between the head 85 of the bolt and the adjacent shackle plate 80. The spring maintains the shackle plates in tight engagement with the cone portions of the shackle 123 bolts. The bolt 81 is provided adjacent the head 85 with a cylindrical enlargement 85^a forming a shoulder to prevent the shackle plates from spreading beyond their initial adjustment. Instead of providing the shoulder 85^a for this purpose a cap similar to the cap 62 may be employed. Also the bolts 53 and 71 and the bolts 99 and 100 hereinafter described are provided with similar shoulders.

Lubricant is supplied to the shackle bolts through openings 88 in the outer shackle plate 80. The openings are arranged centrally of the adjacent recesses 83 and are threaded for the reception of a screw plug 89, but any other suitable form of closure may, of course, be employed and any other suitable means may, of course, be provided for supplying the cone bearings with a lubricant.

In Figs. 14 to 16 inclusive of the drawings is illustrated another form of the invention comprising a single unit or one piece shackle bolt 90 having a central cylindrical portion to fit the eye 91 of a vehicle spring and provided with terminal cone portions 92 which are arranged in cone bearing recesses 93 of adjustable sections 94 of cylindrical formation and arranged in transversely aligned cylindrical openings 95 of depending flanges 96 of a bearing bracket 97 riveted or otherwise secured to the frame or chassis of an automobile or other vehicle. The cylindrical sections 94 are provided with oppositely extending arms 98. The arms of one side of the sections 94 are connected by a continuous bolt 99 and the arms at the opposite side of the sections are connected with the flanges 96 by short bolts 100. The bolts are provided at one end with a head and at the other end are threaded for the reception of a nut. A spring 101 is interposed between the head of the continuous bolt 99 and the adjacent arm 98 and coiled springs 102 are interposed between the heads of the short bolts 100 and the flanges 96.

The bolts maintain a firm engagement between the cylindrical sections 94 and the cone portions of the shackle bolt and are adapted to automatically take up the wear. Any suitable means such as that heretofore described may be provided for supplying the cone bearings with a lubricant.

As illustrated in the drawings one of the sections 94 is provided with a lubricant passage 103 enlarged at the outer end and threaded to provide a threaded socket 104 for the reception of a closure plug 105 similar to the lubricant passages heretofore described to enable a grease gun or similar lubricant supplying device to be connected with the lubricant passage. As the shackle bolt is tubular lubricant will be supplied to each of the cone bearings.

While in the accompanying drawings the improvements are shown applied to several forms of the invention, yet it will be readily understood that the invention is not to be limited to the form shown, but is applicable to any analogous structure in which the improvements may be employed or may be found advantageous.

What is claimed is:

1. In an automatically adjustable connection for shackle bolts, the combination with a

spring having an eye, of a shackle bolt arranged in the eye of the spring and spaced bearings located at opposite sides of the spring for receiving the shackle bolt, said shackle bolt having smooth end portions to 70 slidably fit the spaced bearings and also provided with a central cone portion and said adjustable connection being provided with a tapered opening receiving the cone portion of the shackle bolt and cooperating therewith to 75 form a cone bearing, and tensioning means for urging the shackle bolt in one direction to maintain the cone portion of the shackle bolt in tight engagement with the walls of the tapered opening to take up the wear.

2. In an automatically adjustable connection for shackle bolts, the combination with a spring having an eye, of a shackle bolt arranged in the eye of the spring and spaced bearings located at opposite sides of the spring for receiving the shackle bolt, said shackle bolt having a cone portion and said adjustable connection being provided with a tapered opening receiving the cone portion of the shackle bolt and cooperating therewith to 90 form a cone bearing, tensioning means for maintaining the cone portion of the shackle bolt in tight engagement with the walls of the tapered opening to take up the wear, circumferential grooves being provided at the end portions of the shackle bolt, and means for supplying the cone bearing with a lubricant, said grooves facilitating distribution of the lubricant and operating to prevent the formation of shoulders in the tapered opening. 95

3. An automatically adjustable connection for shackle bolts including a bearing bracket having spaced depending side flanges provided with openings and adapted to receive the eye of a spring between them, a shackle bolt provided with smooth end portions having a sliding fit in the said flanges said shackle bolt having a cone portion located within the said eye of the spring, a bushing arranged within the eye of the spring and having a tapered opening receiving the cone portion of the shackle bolt, and spring tensioning means connected with the shackle bolt for maintaining the same in tight engagement with the bushing. 110

4. An automatically adjustable connection for shackle bolts including a bearing bracket having spaced depending side flanges provided with openings and adapted to receive the eye of a spring between them, a shackle bolt mounted in the said flanges and having a cone portion located within the said eye of the spring, a bushing arranged within the eye of the spring and having a tapered opening receiving the cone portion of the shackle bolt to form a cone bearing, spring tensioning means connected with the shackle bolt for maintaining the same in tight engagement with the bushing, circumferential grooves be- 125

- ing provided adjacent the ends of the bushing, and means for supplying lubricant to the cone bearing, the said grooves facilitating distribution of the lubricant and preventing the formation of shoulders in the cone bearing.
5. An automatically adjustable connection for shackle bolts including a bearing bracket provided with spaced side flanges having openings, a shackle bolt mounted in the openings of the side flanges and provided at one end with a projecting arm spaced from the adjacent flange, said shackle bolt having a cone portion, a bushing adapted to be arranged in the eye of a spring and located between the said flanges and having a tapered opening receiving and fitting the cone portion of the shackle bolt, and means for connecting the said arm with the bearing bracket for guiding the shackle bolt in its inward movement, and separate means for tensioning the shackle bolt to urge the shackle bolt inwardly and maintain the same in tight engagement with the bushing.
6. An automatically adjustable connection for shackle bolts including a bearing bracket provided with spaced side flanges having openings, a shackle bolt mounted in the openings of the side flanges and provided at one end with a projecting arm spaced from the adjacent flange, said shackle bolt having a cone portion, a bushing adapted to be arranged in the eye of a spring and located between the said flanges and having a tapered opening receiving and fitting the cone portion of the shackle bolt to form a cone bearing, means for connecting the said arm with the bearing bracket and for tensioning the shackle bolt to maintain the same in tight engagement with the bushing, circumferential grooves being provided adjacent the ends of the bushing, one of the grooves being formed in the shackle bolt and the other groove in the bushing, and means for supplying the cone bearing with a lubricant, the said grooves facilitating distribution of the lubricant and preventing the formation of shoulders in the cone bearing.
7. An automatically adjustable connection for shackle bolts including a bearing bracket having spaced sides provided with transversely aligned approximately cylindrical extensions, a shackle bolt consisting of a central cone portion and cylindrical end portions of different diameters having a sliding fit in said cylindrical extensions, one of the cylindrical extensions being provided with an exterior recess, arms extending from and rigid with the shackle bolt at one end thereof and spaced from the bearing bracket guiding means carried by the bracket and slidably receiving the arms of the shackle bolt, a nut mounted on the other end of the shackle bolt, a spring arranged in the said recess and tensioned by the said nut, and a bushing arranged between the said extensions and having a tapered opening receiving the cone portion of the shackle bolt to form a cone bearing.
8. An automatically adjustable connection for shackle bolts including a bearing bracket having spaced sides provided with transversely aligned approximately cylindrical extensions, a shackle bolt consisting of a central cone portion and cylindrical end portions of different diameters mounted in said cylindrical extensions, one of the cylindrical extensions being provided with an exterior recess, arms extending from and rigid with the shackle bolt at one end thereof and spaced from the bearing bracket, a nut mounted on the other end of the shackle bolt, a spring arranged in the said recess and tensioned by the said nut, a bushing arranged between the said extensions and having a tapered opening receiving the cone portion of the shackle bolt to form a cone bearing and maintained in tight engagement with the shackle bolt by the said spring.
9. An automatically adjustable connection for shackle bolts including a bearing bracket having spaced sides provided with transversely aligned approximately cylindrical extensions, a shackle bolt consisting of a central cone portion and cylindrical end portions of different diameters mounted in said cylindrical extensions, one of the cylindrical extensions being provided with an exterior recess, arms extending from and rigid with the shackle bolt at one end thereof and spaced from the bearing bracket, a nut mounted on the other end of the shackle bolt, a spring arranged in the said recess and tensioned by the said nut, a bushing arranged between the said extensions and having a tapered opening receiving the cone portion of the shackle bolt to form a cone bearing and maintained in tight engagement with the shackle bolt by the said spring, circumferential grooves being provided adjacent the ends of the bushing, one of the grooves being formed in the shackle bolt and the other groove in the bushing, and means for supplying the cone bearing with a lubricant, the said grooves facilitating distribution of the lubricant and preventing the formation of shoulders in the cone bearing.
10. An automatically adjustable connection for shackle bolts including a bearing bracket having spaced sides provided with transversely aligned approximately cylindrical extensions, a shackle bolt consisting of a central cone portion and cylindrical end portions of different diameters mounted in said cylindrical extensions, one of the cylindrical extensions being provided with an exterior recess, arms extending from and rigid with the shackle bolt at one end thereof and spaced from the bearing bracket, a nut mounted on the other end of the shackle bolt, a spring arranged in the said recess and tensioned by the said nut, a bushing arranged between the said extensions and having a tapered opening receiving the cone portion of the shackle bolt to form a cone bearing and maintained in tight engagement with the shackle bolt by the said spring.

extensions being provided with an exterior recess, arms extending from and rigid with the shackle bolt at one end thereof and spaced from the bearing bracket, a nut mounted on the other end of the shackle bolt, a spring arranged in the said recess and tensioned by the said nut, a bushing arranged between the said extensions and having a tapered opening receiving the cone portion of the shackle bolt to form a cone bearing and maintained in tight engagement with the shackle bolt by the said spring, circumferential grooves being provided adjacent the ends of the bushing, one of the grooves being formed in the shackle bolt and the other groove in the bushing, and a cover washer mounted on the bolt and interposed between the nut and the spring and being of sufficient size to cover the said recess.

11. An automatically adjustable connection for shackle bolts including a bearing bracket having depending flanges, a shackle bolt provided with smooth end portions having a sliding fit in the depending flanges, said shackle bolt being also provided with a cone portion, a bushing having a tapered opening receiving the cone portion of the shackle bolt and located between the said flanges and adapted to receive the eye of a spring, arms extending from one end of the shackle bolt and rigid therewith and arranged in spaced relation with the bracket, a nut arranged on the other end of the shackle bolt, a spring interposed between the nut and the bracket to maintain the shackle bolt in tight engagement with the bushing, and bolts mounted on the bracket and slidably receiving the said arms of the shackle bolt for guiding the latter.

12. An automatically adjustable connection for shackle bolts including a bracket having spaced sides, a shackle bolt mounted in the sides of the bracket and having a central cone portion and provided at one end with arms and having a lubricant passage extending inwardly from such end of the bolt longitudinally of the cone portion and communicating at the inner end with the face of the cone portion, said shackle bolt being provided at the larger end of the cone portion with a circumferential groove, a bushing having a tapered opening receiving the cone portion of the shackle bolt to provide a cone bearing and located between the sides of the bracket and provided at the smaller end of the cone portion of the shackle bolt with a circumferential groove, said grooves facilitating the distribution of lubricant and preventing the formation of shoulders in the cone bearing, spring means for tensioning the shackle bolt to maintain the cone portion in tight engagement with the bushing, and means for connecting the arms of the shackle bolt with the bracket.

13. An automatically adjustable connection for shackle bolts including a bearing bracket

having spaced sides, a shackle bolt mounted in the sides of the bracket and composed of two sections having arms at their outer ends and provided with inner cone portions said sections being also provided with smooth outer end portions having a sliding fit in the sides of the bracket, a bushing having an oppositely tapered opening receiving the said cone portions, bolts connected with the arms and passing through the sides of the bracket, and springs arranged on the latter bolts for tensioning the sections of the shackle bolt to maintain the said sections in tight engagement with the bushing.

In testimony whereof I have hereunto set my hand.

FRANCIS F. JAMES.
